J. J. RYAN

COASTER WAGON

Filed April 7, 1922

UNITED STATES PATENT OFFICE.

JOHN J. RYAN, OF HOPKINS, MINNESOTA.

COASTER WAGON.

Application filed April 7, 1922. Serial No. 550,437.

To all whom it may concern:

Be it known that I, JOHN J. RYAN, a citizen of the United States, residing at Hopkins, in the county of Hennepin and State of Minnesota, have invented certain new and useful Improvements in Coaster Wagons; and I do hereby declare the following to be a full, clear, and exact description of the invention, such as will enable others skilled 10 in the art to which it appertains to make and use the same.

My invention relates to coaster wagons, and has for its object to improve the same in the particulars hereinafter noted.

15 To the above end, the invention consists of the novel devices and combinations of devices hereinafter described and defined in the claim.

In the accompanying drawings, which 20 illustrate the invention, like characters indicate like parts throughout the several views.

Referring to the drawings:

Fig. 1 is a view partly in side elevation and partly in longitudinal section taken on 25 the irregular line 1—1 of Fig. 2;

Fig. 2 is a plan view of the improved wagon with the box removed;

Fig. 3 is a front end elevation with some parts sectioned on the line 3—3 of Fig. 2;

30 Fig. 4 is a detail view with some parts sectioned on the line 4—4 of Fig. 2, on an enlarged scale;

Fig. 5 is a detail view principally in section taken on the line 5—5 of Fig. 3, on an 35 enlarged scale.

Fig. 6 is a fragmentary detail view partly in plan and partly in section, taken on the line 6—6 of Fig. 1;

Fig. 7 is a fragmentary view partly in side 40 elevation and partly in longitudinal section showing a modified form of spring; and

Fig. 8 is a detail view principally in section taken on the line 8—8 of Fig. 7.

Referring first to the improved coaster 45 wagon, as shown in Figs. 1 to 6, inclusive, the numerals 10 and 11 indicate front and rear axles, respectively, having journaled thereon front and rear wheels 12 and 13, respectively, and which wheels, as shown, 50 are of the pressed metal type and are secured on their axles by cotter pins 14 between which and said wheels are interposed washers 15. Mounted on the front axle 10 is a lower bolster 16 formed with a single

flat bar, the end portions of which are folded 55 upon themselves to afford inverted channels 17 in which the front axle 10 is mounted. Nut-equipped bolts 18 are extended through the flanges of the bolster channels 17, below the front axle 10 and to prevent 60 endwise movement of the axle 10, in respect to the bolster 16, said axle is transversely notched at 19 to receive the bolts 18. The ends of the bolster 16 afford stops to limit the axial movement of the 65 wheels 12 onto the axle 10. Washers 20, on the axle 10, are interposed between the bolster 16 and the wheels 12.

Mounted on the lower bolster 16 is a relatively short upper bolster 21, also formed 70 from a flat bar, provided with a central bore to receive a bushing 22 formed by upsetting the lower bolster 16 to pivotally connect said two bolsters. A nut-equipped bolt 23 is extended through the bushing 22 and connects the upper bolster 21 to the lower bolster 16 against lifting movement therefrom. This bolt 23 is provided with a washer 24 which overlaps the upper bolster 21 at its central bore. By reference to Fig. 75 3, it will be noted that the intermediate portions of the bolsters 16 and 21 are offset toward each other, but permit free horizontal swinging movement of the upper bolster 21 and slight tilting movement of said 80 bolster, in respect to each other.

The numeral 25 indicates a pair of longitudinally extended and edgewise spaced spring metal bars, the ends of which are turned downwardly and toward each other 90 to afford front and rear resilient members 26 and 27, respectively. The spring end members 26 rest upon the upper bolster 21, at the ends thereof, and are rigidly secured thereto by rivets or other suitable means. 95 The free ends of the spring members 27 are folded rearward under themselves to afford jaws 28 in which the rear axle 11 is mounted. These jaws 28 are frictionally clamped onto the rear axle 11 by nut-equipped bolts 29, which extend through said jaws, and to prevent endwise movement of the rear axle 11 in the jaws 28, said axle is transversely notched at 30 to receive said bolts.

100 Mounted on the spring bars 25 is a box 31 having transverse cleats 32, which directly rest on said bars and are secured thereto by

nut-equipped bolts 33 which extend through the bottom of the box 31, cleats 32 and spring bars 25.

A tongue 34 is attached to the lower 5 bolster 16 by hounds 35 formed from a single flat bar folded upon itself and attached at its ends to said bolster by nut-equipped bolts 18. The intermediate portion of this bar is curved to form a segmental head 36 which 10 is embraced by a pair of metal straps 37 curved to fit said head and attached to the tongue 34 by nut-equipped bolts 38. A rivet 39 pivotally connects the straps 37 to the head 36 to permit vertical swinging movement of the tongue 34.

Referring now to the modification shown in Figs. 7 and 8, the numeral 40 indicates a spring bar secured to the box 31, under the cleats 32, and its rear end portion is curved 20 downwardly and forwardly to afford a resilient member 41 to which the rear axle 11 is secured by a U-bolt 42. This resilient member 41 is provided with an extension member 43 which projects forwardly and upwardly and engages the spring bar 40 with freedom for longitudinal sliding movement thereon. The extension member 43 is held in its proper relation to the spring bar 40 by a U-bolt 44, the prongs of which are 30 connected by a plate 45 held thereon by nuts 46. This U-bolt 44 extends through the bottom of the box 31, intermediate cleats 32, and its prongs embrace the spring 40 and the extension member 43. The plate 45 on the U-bolt 44 extends under the extension member 43 and is sufficiently loose to permit the required sliding movement of said member under the action of the resilient member 41. The free end of the extension member 43 is bent downward to afford a stop

lug 47 arranged to engage the plate 45 to limit the rearward sliding movement of the extension member 43.

The above described invention has in actual usage proven highly efficient for the purpose had in view, is extremely simple and of comparatively small cost to manufacture. The spring bars 25 afford extremely simple means for attaching the running gear to the box 31 and, at the same time, spring support said box. The resilient members 26 and 27 permit independent up and down and forward and backward movements of the wheels 12 and 13. Obviously, the resilient members 26 and 27 support the box 31 for easy riding movement and in case one of the wheels strikes a stone or other obstruction, the respective resilient member will yield rearwardly and thereby absorb the shock without affecting the easy riding movement of the box 31.

What I claim is:

A coaster wagon comprising a pair of straight longitudinally extended and edge-wise spaced bars, each of said bars having its end portion bent downward and toward each other under the respective bar to form front and rear spring members, the ends of said rear spring members being folded upon themselves to afford jaws, a rear axle mounted in said jaws, nut-equipped bolts extending through said jaws outward of the rear axle and frictionally clamp said jaws thereon, a bolster secured to and connecting the ends of the front spring members, a front axle attached to the bolster, and wheels journaled on the two axles. 75

In testimony whereof I affix my signature.

JOHN J. RYAN.
